Specification for Design.

Patented Nov. 4, 1913.

Application filed August 30, 1913. Serial No. 787,553. Term of patent 14 years.

To all whom it may concern:

Be it known that I, CLINTON E. Woods, a citizen of the United States, and a resident of Bridgeport, Connecticut, (whose post-office address is care of American Graphophone Company, Bridgeport, Connecticut,) have invented a new, original, and ornamental Design for Talking-Machine Frames, of which the following is a specification, reference being had to the accompanying drawing, forming part thereof.

Figure 1 is a perspective view; and Fig. 2 is an end view.

I claim:

The ornamental design for a talking machine frame, as shown.

In testimony whereof I have signed this specification in the presence of two subscribing witnesses.

CLINTON E. WOODS.
